SHELL FOR LAMP SOCKETS

Application filed September 21, 1928. Serial No. 307,357.

This invention relates to improvements in sockets for electric lamps and particularly to socket shells for such sockets.

It is an object of the invention to provide a socket shell which while having reliable resilient contact means for making detachable electric connections to the lamp will be simple, easily made and capable of being produced by machinery at a low cost of manufacture.

With this general object in view, the invention consists in the features, combinations, details of construction and arrangements of parts which will be described in connection with the accompanying drawings and then more particularly pointed out in the claim.

In the drawings:

Fig. 1 is a plan view of a socket shell;

Fig. 2 is an elevation showing a lamp in place in a socket, the socket comprising a socket shell embodying the invention, said shell being shown in elevation;

Fig. 3 is an elevation partly in section of a shell removed from a socket, with a lamp in place in said shell, the lamp being partly broken away, and

Fig. 4 is a side elevation of a spring ring such as that used in the construction shown in Fig. 3.

Referring to the drawings, A is a socket shell formed of sheet metal, such for example as brass, and having the usual screw threads 1 of rounded cross-section for engagement with the socket husk E, and with the lamp base in the usual way.

The outer end of the shell A may have any desired contour but most advantageously has an outwardly flared skirt as indicated at 2.

The inner end of the socket shell A is formed tubular to provide a chamber in which there is placed a movable diaphragm B of insulating material, this diaphragm advantageously being relatively thick so that it may slide within the chamber without tending to cant as it might if too thin. The center of the diaphragm B is provided with a suitable contact device arranged to make contact with the central terminal of an electric lamp, as for example, the central terminal, indicated at 3 of the lamp C. In what is now

considered the best embodiment of the invention the contact device is a tubular sheet metal rivet, indicated at 4, which is inserted in a hole in the diaphragm B and riveted in place by flanging its end edge outward. This contact device has the flanged head of the tubular rivet arranged to come into contact with the central lamp terminal 3, thereby providing a relatively wide and flat contact, thus serving to insure a good contact with the lamp terminal even if the latter is somewhat out of the center of the lamp base.

The extreme inner end of the shell A is flanged inward, as indicated at 5 and between this flange and the diaphragm there is inserted a suitable spring ring D which is specially constructed as an annulus of resilient sheet metal, the annulus being pressed or bent into a series of convolutions as shown for example in Fig. 4 so as to give three points of bearing against the diaphragm B and also three other points of contact against the flange 5 of the shell, the points of contact at one side of the ring D being intermediate the points of contact on the other side of the ring. In the best embodiment of the invention the bearing points of the spring ring on the diaphragm are substantially 120 degrees apart, which tends to give a uniformly distributed spring pressure on the diaphragm and thereby largely reduces if not entirely eliminates any danger of canting the diaphragm which would cause it to lock or stick against the inner walls of the chamber in which it is located.

In assembling the parts the central tubular rivet 4 is riveted to the diaphragm, the spring D is pushed into place and the diaphragm then inserted. To hold the latter in place and to restrict its movement, suitable stop devices are provided. In the simplest form these are protuberances stamped or punched inward from the shell, these being indicated at 6.

In using the shell in the manufacture of sockets, the socket husk, which is usually of pressed or cast insulating material and generally of the form indicated at E, Fig. 2, is threaded onto the two electric conductors indicated at F, Fig. 2, leaving the said con-

ductors projecting a considerable distance beyond the mouth of the socket. Then one of the conductors has its end bared and is inserted into the interior of the hollow rivet 4 where it is secured by solder. When the conductor is of stranded wire, the strands may be spread out so as to form a brush head which will make a good contact with the inner face of the head of the rivet. Then 10 solder may readily be dropped into the hollow rivet to secure the strands in place. The end of the other conductor is soldered to the outer surface of the shell. The socket may then be slid down the conductors and forced onto the shell. It is clear that when an electric lamp 15 C is screwed into the socket shell the outer terminal of the base will make contact with the socket shell while the central terminal of the lamp, indicated at 3, will contact with the head of the rivet 4, whereby, upon screwing the lamp in further, the diaphragm will yield and move back in its chamber, compressing the spring ring D, the spring pressure increasing as the lamp is screwed further 20 into the shell thereby insuring a strong pressure between the head of the rivet and the central terminal of the lamp.

This spring pressure is sufficient to maintain a good contact not only between the central terminal of the socket shell and that of the lamp, but to take up any lost motion in the screw threads and thereby maintain a good contact between the socket shell and the threaded portion of the lamp base which 25 forms its outer terminal.

One of the important features of the invention is that the spring device D cannot cause a short circuit by simultaneously contacting with both terminals of the circuit, and is sufficiently spaced from one terminal or the other that sparking across from the spring device to either terminal is not possible. For example, in the construction shown in the drawings, the spring ring D lies close to and makes 30 an electrical contact with the flanged end 5 of the shell A, but as it is an annulus it is at all points far removed from the central terminal or rivet 4 and from the conductor connected to it, this conductor, of course, being insulated excepting the bared end which is down inside the tubular rivet 4.

By the construction shown and described, the cost of production is greatly reduced, because the parts can be assembled by automatic machines of the types now in common use. For example, the washers B of insulating material and the tubular rivets 4 are supplied to the hoppers or receptacles of automatic machines, which properly assemble the rivet and washer and then rivet, or turn outward, the flange at the open end of the rivet, so as to secure the rivet in place firmly.

The socket shells A, the spring washers D, and the insulating washers B, each carrying 35 its central rivet, are supplied to the hoppers

of automatic machines which feed the parts, one set at a time, to the assembling mechanism. Where the socket shell is held with its outer end upward, the spring washer D is fed into the shell, then an insulating washer B is 70 pushed into the shell on top of the spring washer, and while the insulating washer is pressed down slightly against the spring washer, the protuberances 6 are pressed or punched inward to hold the parts in their 75 assembled positions. Owing to the use of an annular spring washer, there is practically no danger of the washer clogging the feed chute or hopper of an automatic machine. Hence, 80 the feeding of the parts proceeds with certainty.

It will be seen that the socket shell A with its contained parts is a complete unit which can be shipped safely to another plant where the husks E are made and the socket shell assembled with it and the conductors. Usually 85 the socket shells are made at one factory and the finished socket made at another factory.

By the construction of socket shell with its contained parts as heretofore described, 90 the labor of completing the socket, which heretofore has been largely hand labor, is materially reduced.

What we claim is:

A metallic socket shell for lamp-sockets 95 comprising a threaded portion arranged to receive the threaded base of an incandescent lamp, an end portion forming a tubular chamber and terminating in an inwardly extending annular flange, a movable cylindrical diaphragm of insulating material located in said chamber, a central terminal secured at the center of the diaphragm, a spring within the socket shell arranged to press the diaphragm 100 at a plurality of points and said flange at a plurality of points and to urge the central terminal toward an incandescent lamp, said spring being prevented by said shell from contacting with said central terminal, said shell, spring and diaphragm being relatively 105 rotatable in assembled position, and means 110 formed integrally with the socket shell for limiting forward movement of the diaphragm in the chamber.
